WEARING APPAREL

Dorothy Dyar Penniman, Washington, D.C.

Application September 26, 1956, Serial No. 612,296

6 Claims. (Cl. 2—76)

This invention relates generally to wearing apparel which is designed to be fitted for normal wear but which is adaptable to the changes in contour of the body of a wearer, such as occasioned by pregnancy or abdominal obesity.

Many previous attempts have been made to provide wearing apparel with adjustable features designed to accommodate an increase and/or a decrease in the waistline or abdominal contours of a wearer, but all of these attempts of which I am aware, have not been entirely satisfactory since in many instances they sacrifice appearance for comfort, while others have produced garments which have temporary utility only.

It is an object of my invention to provide a garment of the character described which is readily adaptable to the changing contours of the body of the wearer thereby to provide the desired comfortable support which comes from substantially complete conformity of the garment to the contours of the body, while providing a generally neat and trim appearance for the wearer.

Another object of the invention is to provide a garment of the character described which may be worn by expectant mothers, and which due to the novel design features of the garment, may be worn with equal comfort, before, during and after pregnancy, while maintaining throughout a neat and trim appearance.

A further object of my invention is to provide in a garment of the character described plural areas of expansion in the vicinity of the waistline or abdominal region thereof to insure a full measure of expansion in the garment where most needed and positioning said areas at points which will insure maximum comfort for the wearer.

A further object of my invention is to provide in a garment of the character described means to conform and fit the garment snugly to the body of the wearer along a line immediately below the lower extremity of the abdomen and coinciding substantially with the pubic bone so as to maintain the skirt firmly in place at this point to insure the maintenance of an even hem line and enhance the overall neat and trim appearance of the garment.

A further object of my invention is to provide a general principle of design for wearing apparel which is of general applicability to men's and women's garments, including sportswear, but which is of particular utility in respect to women's skirts and dresses.

These and other objects of my invention will become apparent from a consideration of the following specification read in the light of the accompanying drawings wherein—

Fig. 1 is a diagrammatic front view of a skirt made in accordance with my invention;

Fig. 2 is a diagrammatic rear view of the skirt of Fig. 1;

Fig. 3 is a diagrammatic side view of the skirt of Fig. 1;

2

Fig. 4 is a diagrammatic plan view of the front panel of the skirt of Fig. 1, before sewing;

Fig. 5 is a diagrammatic front view of a dress made in accordance with my invention;

Fig. 6 is a diagrammatic plan view of the front panel of the dress of Fig. 5;

Fig. 7 is a diagrammatic front view of a bifurcated garment made in accordance with my invention;

Fig. 8 is a diagrammatic plan view of a front panel 10 to be incorporated in a garment of Fig. 7.

Referring more particularly to the accompanying drawings in which like reference numerals are used to designate like parts throughout, Fig. 1 shows a skirt made in accordance with my invention and the same 15 comprises a multiple gore front panel comprising three gores, 1, 2 and 3, joined by sewed seams 4 and 5. The rear portion of the skirt may be conventionally formed and may include any desired number of gores such as 6 and 7 as shown in Fig. 2. The gores 6 and 7 are joined by a sewed seam 8 and the thus joined rear gores are joined at the outside edges to the corresponding edges of the front panel gores 1 and 3 by sewed seams 9 and 10.

The front panel of the skirt may conveniently be made in one piece as shown in plan in Fig. 4 wherein the gores 1, 2 and 3 are formed integral with the top front portion 11 of the skirt. The material from which the skirt is to be made is cut out at 12 and 13 to form the gore pieces 1, 2 and 3 in spaced relation as shown. I thus provide areas of fullness in the top portion 11 of the skirt as shown at 14 and 15 in Fig. 1, when the adjacent edges 16 and 17, and 18 and 19 of the gore pieces 1, 2 and 3 are sewed together. It will be noted that the seams 4 and 5 which join the edges 16 and 17, and 18 and 19, respectively, extend from the bottom edge of the front panel upwardly to points indicated at 20 in Fig. 1.

These points as shown are spaced on opposite sides of the center line C—L of the front panel of the skirt on a line D—D which coincides substantially with the pubic bone or with the lower terminus of the abdominal region of the wearer. Having in mind the cut out portions 12 and 13 as shown in Fig. 4, it is apparent that by terminating the seams 4 and 5 at the points 20 as shown, the top portion 11 of the skirt, above and in general alignment with the seams 4 and 5 will fold as shown at 14 and 15 to provide areas of fullness at these points, the expansive extent of which depends upon the transverse dimension of the upper portion of the cut out portions 12 and 13. The material of these folds is preferably disposed as shown in Fig. 1, so as to lie on opposite sides of the abdomen of the wearer forwardly of the hips. This even distribution of the surplus material of the upper part of the skirt at opposite sides of the abdomen insures the maximum degree of comfort for the wearer while providing ample material to accommodate the expanding contours of the body.

The lower edges 21 of the upper part 11 of the skirt which connect the gores 1, 2 and 3 as shown in Fig. 4, become the lower extremities 22 of the respective infolded portions 14 and 15 of the skirt, when the gore seams 4 and 5 are formed in Fig. 1, and the gore seams 4 and 5 are carried slightly above the extremities 22 of said infolded portions as shown. The ends 22 may be secured together if desired, but it is preferred to leave these ends unsewed as this facilitates the distribution of the material within the sections 14 and 15 when the latter expand to conform to increasing body contours. The waistline of the skirt comprising the upper edge 23 of the front panel and the upper edge of the rear panel 70 of the skirt may be finished in any conventional manner, preferably without the use of a built-in belt or stiffening material, since it has been found more convenient and

practical to obtain the desired snug fit at the waistline by the use of safety pins, ornamental or otherwise. However, any form of belt, snap fasteners or lacing may be employed to secure the top portions of the skirt in place or, if desired, a sash, scarf or cummerbund (not shown) may be employed to cover the area of the skirt between the line D—D and the top of the skirt including the outer corner portions 24 of the infolded portions 14 and 15.

As is well known, the general expansion of the human body in the abdominal region normally tends to distort the apparel of the wearer and cause it to assume unnatural and unsightly lines. This is particularly true with dresses and skirts which are prone to draw up in the front and dip down in the back and this destroys entirely the hang or drape of the skirt and the desirable even hemline. In order to avoid these objectionable features in the present garment, I provide means to conform the same firmly and snugly to the body of the wearer at the pubic region or immediately below the abdomen of the wearer. This region is indicated by the line D—D in the drawings and it marks the upper termini of the seams 4 and 5. This portion of the dress or skirt is closely fitted to the body of the wearer by proper transverse dimensioning of the gores 1, 2, 3, 6 and 7 and/or adjustment at the side seams 9 and 10. The garment may be transversely reinforced across the front in substantial coincidence with the pubic region of the wearer by adjustable tie tapes 25. These tapes are secured to the inside front portion of the garment as shown in Figs. 1 and 3 and extend from one side seam of the garment to the other and are provided with unattached end portions which are adapted to be secured together in the rear, with the tapes encircling the body of the wearer at the pubic bone region, in order to preclude stretching of the garment due to the wearer kneeling, sitting down or assuming a squatting position. Thus the lower extremities 22 of the infolded portions 14 and 15 extend slightly below said tapes, as shown, and lie between the tapes and the front inside portion of the garment which overlie the respective infolded portions 14 and 15. This arrangement avoids any possible interference between the tapes and the lower ends 22 of the infolded portions 14 and 15, during expansion of the latter. If desired, a conventional lining, not shown, may be inserted in the front portion of the garment to further reinforce the garment against stretching, as it is important to maintain this firm snug fit of the garment at the pubic region in order to maintain the proper and desirable fall of the lower portion of the skirt, as well as a substantially even hem line.

The skirt is preferably designed to accentuate a generally "slim line" and may be conventionally flared slightly at the hem line as shown, to provide more comfort in walking. Also, if desired, a "split" or inverted "kick pleat" as shown at 25a may be provided at the rear of the skirt. It will, of course, be understood that while I have shown a skirt having a three-gore front panel and a two-gore rear panel, this is but for the purpose of illustration only and the number of gores employed may be varied as desired.

The design features which characterize the skirt of Figs. 1 to 4 are also applicable to a garment such as a dress, and I have shown in Figs. 5 and 6 the manner in which a dress comprising a skirt portion 26 and a blouse portion 27 may be made. The front panel of the dress may be made from a single piece of material cut as shown in Fig. 6 and comprising skirt forming lower gore members 28, 29 and 30 separated by cut out portions 31 and 32, and blouse forming upper gore members 33, 34 and 35 separated by cut out portions 36 and 37. The opposed adjacent edges of the gore members are sewed together along seam lines 38 and 39 as shown in Fig. 5 to form the front portions of the blouse and skirt respectively, it being noted that the gore seams

39 of the skirt terminate at the line D—D which coincides with the pubic line and marks the lower terminus of the abdominal region of the wearer, while the gore seams 38 in the blouse, terminate at the line D'—D' which marks the upper extremity of the abdominal region. Between the lines D'—D' and D—D the fullness of the central portion 40 of the dress occasioned by the cut out portions 31—32 and 36—37 as shown in Fig. 6 is gathered in infolded pleats 41 which lie on opposite sides of a center line C—L of the dress front, and are disposed to occupy positions on opposite sides of the abdomen of the wearer, forwardly of the hips. It will be noted that the gore seams 38 and 39 extend from opposite ends of the front panel towards the waistline of the dress, but terminate at points in longitudinally spaced relation lying above and below that portion of the panel which is adapted to overlie the abdominal region of the wearer. This provides the necessary fullness in the abdominal region of the dress to accommodate body expansion while distributing said fullness in a manner to insure the comfort of the wearer.

As previously described in connection with the skirt shown in Figs. 1 to 4, the skirt portion 26 of the dress shown in Figs. 5 and 6 is fitted to snugly and firmly engage the body of the wearer along the line indicated generally at D—D, by properly dimensioning the gore elements 28, 29 and 30, or by adjusting the side seams 42 by which the front panel of the dress is sewed to a back panel of conventional form (not shown). Reinforcing tapes 40a, similar to those shown at 25 in Fig. 3, may be employed if desired. By thus closely fitting the skirt portion 26 of the dress to the body of the wearer at the pubic region thereof, the lower portion of the skirt falls freely from this point, thereby maintaining a substantially even hemline and precluding all tendency of the skirt to "ride up" in front.

It is apparent from the foregoing description that I have designed a garment in which ample fullness is provided in that portion which is adapted to overlie the abdominal region of the wearer, to accommodate expanding body contours due to pregnancy or abdominal obesity, and have so disposed and distributed the material of the garment which provides such fullness, that no sacrifice in comfort or appearance has been made. This enables one to wear a garment embodying the features of the present invention, with equal comfort before, during and after the time when the waistline of the wearer assumes abnormal proportions. Thus the garment of the present invention may be worn at any time as a normal article of wearing apparel in addition to being of service in times of pregnancy and/or obesity. Furthermore, by the novel design features by which the skirt or dress is supported in a manner to insure proper hang or fall, a neat trim appearance is afforded the wearer, and a trim even hemline is assured. The neat trim appearance of the wearer may be further enhanced if a free-hanging jacket or blouse is worn, having a length such that the lower edge thereof coincides substantially with, or falls slightly below, the line D—D.

It should be noted that the same principles of design which have been utilized in the skirt and in the dress shown in the drawings, may be utilized to provide a bifurcated garment, such as shorts or slacks, such as shown in Fig. 7. Thus, if a front panel such as shown in Fig. 8 is formed, similar in all respects to that shown in Fig. 4 except that the central gore 43 thereof is made slightly wider than the central gore 2 of the skirt panel of Fig. 4, the central gore 43 may be bifurcated along the line 44 coinciding with the center line of the panel and the opposite sections 43a and 43b thereof may be joined to the opposite side gores 45 and 46 by sewing together the respectively adjacent edges 47 and 48. Front portions of leg members 49 and 50 are thus formed, the seams joining said gore sections being indicated at 51. These seams are disposed generally centrally of the leg

members and extend from the bottom edges thereof upwardly to the line D—D which passes substantially through the pubic region or lower extremity of the abdominal region of the wearer. The upper termini of the seams 51—51 are indicated at the points 52 and the upper part of the garment at points in general vertical alignment with the seam 51—51 is provided with dual areas of fullness which are indicated by the infolded pleated portions 53. The rear portion 54 of the bifurcated garment shown in Fig. 7 may be formed in any conventional manner and comprise one or more gores, and said rear portion 54 may be joined to the front portion along side seams 55 and inner leg seams 56, as shown. The upper portion of the garment of Fig. 7 may be provided with any conventional form of placket or fly indicated at 57, or, if desired, a rear or side placket (not shown) may be provided in lieu thereof, if the garment is designed to be worn by a female. Also, adjustable tie tapes as shown at 51a and similar in all respects to those described in respect to Figs. 1 and 3, may be employed to insure a firm snug fit of the garment through the pubic region of the wearer and thus enhance the general appearance thereof.

It will be understood that the reference herein to a "one piece" panel member is not to be construed as a limitation in this respect since the panel may be constructed of several pieces, if desired, so long as the general design of the panel member as shown in Figs. 4, 6 and 8 is maintained. The use of the one-piece construction as suggested is particularly convenient since it permits the use of 36-inch dress material and reduces the time and labor of the dressmaker to a minimum but the invention is in no way limited to this construction.

In conclusion, it will be understood that while I have shown and described preferred embodiments of my invention, these are but for the purposes of illustration only and those skilled in the art will realize that various changes may be made in the size and proportion and arrangement of parts without departing from the spirit of my invention, the limits of which are defined more clearly in the appended claims.

I claim:

1. A garment adapted to conform to the changing contours of the body of a wearer during pregnancy comprising a skirt having embodied therein a front panel member extending substantially the full length of the skirt and having a widthwise extent to cover the abdominal and pubic regions of the wearer, said front panel member having a pair of spaced elongated generally vertically disposed cutouts, one on each side of the median line of said panel and extending upwardly from the lower edge of the skirt and terminating in that portion of the garment designed to overlie the pubic region of the wearer, the adjacent longitudinal edges of each of said cutouts being joined together, said cutouts having a substantial widthwise extent at the top thereof, the material of the said panel above the cutouts providing pleat forming material when the longitudinal edges of the cutouts are joined together, said pleat forming material above each cutout being folded upon itself to form pleats in 60 the abdominal covering region of the garment.

2. The garment described in claim 1 wherein the longitudinal edges of said cutouts are downwardly and inwardly inclined whereby to give the finished skirt a desired degree of flare at the bottom.
3. The garment described in claim 1 wherein the expandable pleats are infolded and open towards each other on opposite sides of the median line of the front panel.
4. The garment described in claim 1 wherein the panel member is provided with a transversely extending skirt constricting member secured to the inner face of the panel substantially at the upper extremities of said cutouts.
5. The garment described in claim 4 wherein said skirt constricting member comprises a band of flexible material sewed to the inner face of the panel, said band including free end tie portions adapted to encircle the body of the wearer.
6. A dress adapted to conform to the changing contours of the body of a wearer during pregnancy comprising a blouse portion and a skirt portion, a front panel member extending substantially the full length of the dress and having upper and lower portions embodied in the blouse and in the skirt portions of the dress respectively, said panel member having a widthwise extent to cover the abdominal and the pubic regions of a wearer, the lower portion of the panel member having a pair of spaced elongated generally vertically disposed cutouts, one on each side of the median line of the panel member and extending upwardly from the lower end of 20 the panel member and terminating below the abdominal covering portion of the dress in that portion thereof designed to overlie the pubic region of the wearer; the upper portion of the panel member having a pair of spaced elongated generally vertically disposed cutouts, one on each side of the median line of the panel and extending downwardly from the upper edge of the panel member and terminating above the abdominal covering portion of the dress, said cutouts in the upper and lower portions of the panel member being in general vertical alignment and having substantial widthwise extent at their inner ends, the longitudinal edges of the respective cutouts being joined, the material of the panel member between the adjacent inner ends of the vertically aligned cutouts providing pleat forming material when the longitudinal edges of said cutouts are joined, said pleat forming material being folded to form pleats extending longitudinally of the panel in the abdominal covering portion thereof.
